Cyrus N. Anderson
ATTORNEY.

UNITED STATES PATENT OFFICE.

ANTONIO PAPINI, OF PHILADELPHIA, PENNSYLVANIA, ASSIGNOR TO JOSEPH H. LYNCH, OF ASBURY PARK, NEW JERSEY.

CLASP.

1,412,088.

Specification of Letters Patent. Patented Apr. 11, 1922.

Application filed February 5, 1921. Serial No. 442,618.

To all whom it may concern:

Be it known that I, ANTONIO PAPINI, a subject of the King of Italy, and a resident of Philadelphia, in the county of Philadelphia and State of Pennsylvania, have invented an Improvement in Clasps, of which the following is a specification.

My invention relates to clasps, and in the accompanying drawing I have illustrated 10 the same as embodied in a construction which is adapted for use in laundries for attachment to articles being laundered to identify the same, but the principle of the said invention may be employed and embodied in clasp 15 constructions of various kinds for various purposes and uses.

One object of the invention is to provide a clasp which is durable and efficient in action, which is simple in construction and 20 which is relatively thin and flat.

A further object is to provide an improvement in the means of locking or attaching the clasp to an article, such as an article of 25 wearing apparel, a bag for closing the same, and other like articles.

Other objects and advantages of the invention will be pointed out in the detailed description thereof which follows or will be apparent from such description.

In order that the invention may be readily understood and its practical advantages 30 fully appreciated, reference may be had to the accompanying drawing in which I have illustrated certain convenient forms of embodiment thereof. It will be understood 35 that the invention is susceptible of embodiment in other forms of construction than those shown and that changes in the details of construction may be made within the 40 scope of the claim without departing from the said invention.

In the drawing:

Fig. 1 is a top plan view of a clasp embodying my invention with the locking member 45 in locking position and showing a portion of fabric in dash and dot lines to which the said clasp is attached;

Fig. 2 is a longitudinal sectional view taken on the line 2—2 of Fig. 1;

Fig. 3 is a bottom plan view of the clasp 50 shown in Fig. 1;

Fig. 4 is a view in side elevation of the clasp looking toward the left in Fig. 1, one

edge of the portion of fabric indicated in Fig. 1 being shown; 55

Fig. 5 is a view in side elevation of the clasp but with the locking member thereof in unlocked position and with the clamping or gripping jaws in spaced or separated relation with respect to each other; 60

Fig. 6 is a transverse sectional view taken on the line 6—6 of Fig. 1;

Fig. 7 is a similar view taken on the line 7—7 of Fig. 1;

Fig. 8 is a top plan view of a slightly 65 modified construction of clasp;

Fig. 9 is a bottom plan view of another modified construction of clasp embodying my invention, the locking member thereof being in locking position; 70

Fig. 10 is a view in side elevation of the clasp shown in Fig. 9, the locking member being in unlocked position; and

Fig. 11 is a transverse sectional view taken on the line 11—11 of Fig. 9. 75

Referring to the drawing: 1 and 2 designate the top and bottom sides respectively of a clasp, the said two sides being formed by bending a strip of suitable metal as shown. The bottom 2 of the clasp is provided with indentations or corrugations 3 extending transversely thereof which provide means to facilitate the handling of the clasp in operating the locking plate 4, which is slidably connected with the top side 1 of 80 the clasp, although the arrangement may be reversed and the locking member or plate slidably connected with the bottom side 2. The locking plate 4 likewise is provided with indentations or corrugations 5 which 85 provide means for facilitating the movement of the same into and out of locking position with respect to the top side 1.

As already stated, the portion of the clasp comprising the top and bottom sides 1 and 2 is formed by bending a strip of suitable metal at a point intermediate its ends as shown, and for convenience of description the part of the clasp comprising the sides 1 and 2 may be described as being of U-shape. 95

Adjacent its forward free end the bottom side 2 is provided with a number of perforations 10. There are four of these perforations in the construction shown, but it will be understood that the number of these 100 perforations may be changed without departing

from my invention. The forward end portion of the top side 1 of the clasp is provided with projections 11 formed by upsetting or indenting the material of the said side 1, which projections are adapted to enter the openings or holes 10 when the sides 1 and 2 are in clamping or gripping relation with respect to each other, in which position they are held by means of the locking device 4.

Referring now to Figs. 1 to 8 inclusive, the locking member or plate is slidably secured to the top member 1 by means of projections 15 at its opposite edges which extend toward and transversely of the said top side 1 and are provided with inwardly turned portions 16 which overlie the inner side or inner surface of the said top side 1, as is clearly indicated in the drawing, particularly Fig. 6. The inwardly turned end portions 16 of the projections 15 slidably engage the inner surface of the top side 1 of the U-shaped member of the clasp. Forwardly of the projections 15 the locking member or plate 4 is provided with outwardly extending projections 20 at its opposite edges, the outer edges of which are inclined as indicated at 21 and are adapted to engage the correspondingly inclined underneath surfaces of the inwardly extending end portions 22 of the projections 23 which project from the opposite edges of the bottom side 2 of the U-shaped member of the clasp. The said projections 23 extend toward and transversely of the top side 1 of the U-shaped clasp member, as is clearly indicated in the drawing. The inclined surfaces 21 upon the projections 20 co-operate with the inclined surfaces upon the underneath sides of the inwardly extending portions 22 of the projections 23 to effect a wedging action for clamping the opposite top and bottom sides 1 and 2 of the U-shaped clasp member together, as is shown in the drawing, particularly Figs. 2 and 4. These co-operating wedge acting surfaces may be regarded as cams in view of the fact that as the locking member is moved forward into the position shown in Figs. 1, 2, 3 and 4, the inclined surfaces 21 of the upper edges of the projections 20 contact with and slide forwardly with respect to the inclined underneath surfaces of the inwardly extending portions 22 of the projections 23.

It will be noted that the projections 11 in the various forms of construction are of considerably less diameter than the diameters of the openings 10. The purpose of this is to prevent the said projections from perforating the material 25 of the article to which the clasp may be attached. As is indicated in Fig. 2, the portions of the material 25 between the projections 11 and the holes 10 is pressed down into the holes and the portion which is pressed down surrounds

the projections 11. However, in view of the width of the annular space between the projections 11 and the edges of the opening 10, the material is not perforated or cut; in other words, it is not in any way injured, although the clasp is securely attached to the article.

In the construction shown in Figs. 1 to 7 inclusive the bottom side 2 of the U-shaped member of the clasp is provided with an enlarged extension 30 of rectangular shape having a rectangular opening 31 therein through which a supporting cord, wire or the like may pass for the purpose of suspending the clasps having the articles which have been laundered attached thereto. The construction shown in Fig. 8 is identical with that shown in Figs. 1 to 7 except for the difference in the shape of the extension 32 which in Fig. 8 is practically circular and is provided with an opening 33 for the same purpose as the rectangular opening 31 in the extension head 30. The purpose of employing the heads or extensions of different shape is to provide means for quickly distinguishing or differentiating the articles which are being laundered. For instance, it may be that certain batches of laundry are to be delivered wet or perhaps merely rough dried to the owners thereof, whereas other batches are to be ironed. In such cases it is desirable that clasps having, for instance, round headed extensions be placed upon one class of such batches, say those which are to be delivered wet or merely rough dried, while clasps having rectangular shaped extensions will be employed upon the articles of the batch or batches which are to be ironed. It will be seen, therefore, that a ready means is provided to differentiate between the two classes of laundry.

In the modified construction shown in Figs. 9 to 11 inclusive, the opposite edges of the locking member of plate 4 are provided with flange-like projections, as indicated at 35, the said projections extending transversely of and occupying positions in the plane of the top side 1 of the U-shaped portion of the clasp. The rear parts of these flanges 35 are provided with inwardly extending projections 36 of considerable length which overlie the inner surface of the top side member 1 and slidably connect the locking member or plate 4 to the said top side 1. The forward portions of the said flanges 35 are likewise bent inwardly, as indicated at 37, but the width of said inwardly bent portions is less than that of the inwardly bent portions 36. The inwardly bent portions 37 are adapted to slidably engage with the inclined underneath sides of the outer end portions of projections 40 which extend outwardly and are inclined inwardly from the opposite edges of the bottom side 2 of the U-shaped mem-

ber of the clasp device. By the term "inwardly" just used it is meant to convey that the projections 40 extend toward the plane of the top side 1 of the said U-shaped member.

It will be noted that the shape of the flanges and the inturned edges thereof upon the locking member or plate shown in Figs. 9, 10 and 11 differ from the shape of the corresponding portions of the structure shown in the preceding figures of the drawing, also that the construction and shape of the interlocking wedge acting projections 37 and 40 differ from the construction and shape of the corresponding parts of the preceding figures of the drawing. Except for these differences the construction shown in Figs. 9 to 11 inclusive is substantially identical with the constructions shown in the preceding figures of the drawing.

In the employment of the clasps of this character numbers are placed at some convenient place thereon, as for instance, upon the forward top side portion of the locking member or plate, as indicated at 41, for identifying the articles to which the clasps may be attached. For instance, let us assume that a customer sends a number of articles to a laundry to have the same laundered;—a number is assigned to such customer and before the articles are laundered a clasp bearing that particular number is attached to each article. It is apparent that when this is done there will be no difficulty

in segregating the different batches of articles belonging to different customers and placing them all together in separate groups or batches.

Having thus described my invention, what I claim and desire to secure by Letters Patent, is:

A clasp of the character described, comprising a U-shaped member one side of which is provided with projections which extend toward and beyond the other side of said member and terminate in inwardly extending portions which incline toward the forward end of said side, and a locking member upon the outer side of the other side of such U-shaped member, said locking member having means at its opposite edges in slidable engagement with the opposite edges of the said other side whereby said locking member is slidably connected with said other side, and the said locking member having outwardly extending projections at its opposite edges forward of said means, the outer edges of which projections are inclined toward the forward end of said clamping member and adapted to engage the inwardly extending inclined portions of the projections upon the first named side of said U-shaped member.

In testimony that I claim the foregoing as my invention, I have hereunto subscribed my name this 2nd day of February, A. D. 1921.

ANTONIO PAPINI.
